UNITED STATES PATENT OFFICE.

SAMUEL H. TINSMAN, OF FORT MADISON, IOWA.

PLANTER.

No. 893,886.

Specification of Letters Patent.

Patented July 21, 1908.

Application filed September 20, 1906. Serial No. 335,370.

To all whom it may concern:

Be it known that I, SAMUEL H. TINSMAN, a citizen of the United States of America, and resident of Fort Madison, Lee county, Iowa, have invented a certain new and useful Improvement in Planters, of which the following is a specification.

My invention relates to seed-planting machines of the type known as listers—that is to say, planting machines in which a double mold board furrow-opener is combined with seed-dropping mechanism operated by the supporting wheels of the planter, and in which the corn or other seed is dropped in the furrow made by said furrow-opener as the planter is drawn over the field.

Generally stated, the object of my invention is the provision of an improved and highly efficient seed-planting machine of the so-called lister type.

Special objects are to provide an improved general construction; to provide improved means for operating the seed-dropping mechanism; to provide improved means for controlling the seed-dropping mechanism when the planter is raised and lowered; to provide an improved arrangement in which the axle of the forward wheels can be rocked to raise and lower the furrow opener in the frame; and to provide certain details and features of improvement and combinations tending to increase the general efficiency of a seed-planting machine of this particular character.

To the foregoing and other useful ends, my invention consists in matters hereinafter set forth and claimed.

In the accompanying drawings, Figure 1 is a side elevation of a lister embodying the principles of my invention, the near wheel being removed for convenience of illustration; Fig. 2 is a plan of the lister shown in Fig. 1; Fig. 3 is a longitudinal section of said lister; Figs. 4 and 5 are details of the means for operating and controlling the seed-dropping mechanism within the hopper; Fig. 6 is a view similar to Fig. 1, but showing the furrow-opener lowered to the ground; Fig. 7 is a detailed section on line 7—7 in Fig. 6.

As thus illustrated, my improved lister comprises a double mold board furrow-opener A, which is mounted upon a forward extending beam a. This beam is supported at its forward end by the upper portion of a

bail-shaped axle B, and at its rear end by a swinging bail C. The said axle is supported in the hubs of wheels D. The said bail is supported in brackets e, which are secured to the body frame E. It will be seen that this body frame is U-shaped in form, having its rear end supported by the double caster wheel F, which latter is free to swing or caster from side to side. The said axle B is supported in bearings b secured to the forward end portions of the said U-shaped frame. A spring G connects the rear cross-piece of said body frame with the said beam a of the furrow-opener, thus assisting in raising the latter from the ground. With the arrangement shown provision is made for attaching draft devices to the forward end of the said beam a. A clip H is fastened to the said beam and carries an ordinary sod cutter or colter I, which latter runs ahead of the double mold board furrow-opener. The rotary covering disks J are secured to the rear ends of the two mold boards of the furrow-opener, and arranged in position to assist in throwing the dirt over the seed dropped from the delivery spout K. It will be seen that this spout extends downwardly to the point just in the rear of the heel of the said furrow-opener. The double caster wheel F comprises two wheels which tend to push the dirt toward each other, thus assisting in covering the seed dropped by the planter.

A driver's seat L is suitably mounted and supported upon the rear portion of the U-shaped body frame. At its forward portion, the two ends of the U-shaped frame are connected through the medium of two uprights M and a bearing or casting m, as shown more fully in Fig. 5. This, in effect, provides an arch at the forward end of the body frame, and upon this arch is mounted the hopper N which contains the seed-dropping mechanism of any suitable known or approved type. The said seed-dropping mechanism is operated by a horizontal shaft m' supported in said bearing m and provided with a bevel gear m², which engages the rotary plate m³ on the bottom of the said hopper. A sprocket wheel m⁴ is secured to the other end of said shaft and a spring m⁵ is supported between the said sprocket wheel and a bracket arm m⁶ which extends around from the casting m. A collar m⁷ is keyed or otherwise secured to said shaft, and a slotted link or arm O is inter-

posed between the said collar and the said portion m^6 . It will be observed that the slot o in said link or arm permits the latter to move up and down upon the said shaft. It will also be seen that the cam portion o' on the said link or arm will engage the collar m^7 and cause the bevel gear m^2 to disengage from the rotary plate m^3 , when the said link or arm O is moved upwardly. At its lower end the said link or arm is pivotally connected with one arm or vertically swinging portion of the bail-shaped axle, as, for example, by means of a clamp or bracket o^2 secured to said axle (see Fig. 6). A sprocket wheel P is secured to a sleeve on said axle, which sleeve engages or connects with the adjacent supporting wheel D , whereby the said sprocket wheel rotates when the planter is traveling along. A sprocket chain Q connects the sprocket wheel P with the sprocket wheel m^4 , as shown more clearly in Fig. 6, and with this arrangement the rotation of the wheel D is accompanied by the rotation of the shaft m' . If the bevel gear m^2 is in engagement with the seed-dropping mechanism, the latter is then operated. On the other hand, if the furrow-opener is raised from the ground, and the axle B thus swung into the position shown in Fig. 1, it is obvious that the seed-dropping mechanism is thereby rendered inoperative, by reason of the endwise shifting of the shaft m' . When the furrow-opener is down, as shown in Fig. 6, the cam portion o' then disengages from the collar m^7 , permitting the shaft m' to shift endwise under the pressure of the spring m^5 , causing the bevel gear m^2 to reengage the mechanism of the seed-dropping devices at the bottom of the hopper. When this is done, the seed-dropping mechanism is operated, and the seed discharged from the hopper is conducted through a pipe or hollow connection R to the spout K , and then dropped in the furrow made by the furrow-opener A . The seed is then covered up, or partially so, in a manner previously described, and according to the adjustment of the disks J and the wheels F .

A hand lever S is secured to one spindle or end portion of the axle, and is provided with locking means adapted to engage the tooth-locking rack T , which latter, of course, is rigidly secured to the frame E . With this arrangement the driver can rock the shaft and thereby raise and lower the furrow-opener, and at the same time automatically control the connections between the wheel and the dropping mechanism. It will be seen that the spindles of the axle, and the axis about which the wheels rotate, are located substantially above the point or toe of the furrow-opener, thus facilitating the turning around of the planter.

It will be seen that the covering disks J are provided with pivoted bearings j , where-

by these disks can be adjusted about vertical axes, so as to vary the angle of each disk according to requirements.

What I claim as my invention is:—

1. In a planter, a furrow opener seed-dropping mechanism, an endwise movable shaft provided with means for engaging said mechanism, means for automatically shifting said shaft endwise when the furrow opener is raised and lowered, a wheeled frame supporting said mechanism and furrow opener, and means for raising and lowering said furrow opener without raising or lowering said shaft and mechanism. 70

2. In a planter, a furrow opener seed-dropping mechanism, an endwise movable shaft provided with means for operatively engaging said mechanism, a sprocket wheel on said shaft, a spring tending to keep the shaft in position to operate the said seed-dropping mechanism, a vertically disposed and endwise movable slotted arm through which the shaft extends, a cam on said arm, means on said shaft for engaging said cam, means for automatically moving the said arm up and down when the furrow opener is raised and lowered, a wheeled frame supporting the said mechanism, bails supporting the furrow opener on said frame, and means for raising and lowering said furrow opener without 95 raising and lowering said mechanism and shaft. 80

3. In a planter, a U-shaped frame, a bail-shaped axle journaled in bearings on the forward end portions of said frame, a swinging bail journaled in bearings on the rear portion of said frame, a double mold board furrow-opener provided with a beam, bearings on said beam for engaging said bail and axle, an arch across the forward portion of said frame, seed-dropping mechanism mounted on said arch, wheels on said axle, means for rocking said axle to raise and lower the furrow-opener in the frame, and means operated by the said axle for automatically connecting and disconnecting the said seed-dropping mechanism when the furrow-opener is lowered and raised. 100

4. In a planter, the combination of a double mold board furrow-opener, a body frame, a bail-shaped axle supported in bearings on said frame, a swinging bail supported in bearings on said frame, means for connecting the furrow-opener with the said bail and axle, a support at the forward end of said frame, seed-dropping mechanism mounted upon said support, a driver's seat supported on the frame in rear of said seed-dropping mechanism, a seed-delivering spout in rear of said furrow-opener, a pipe connecting the seed-dropping mechanism with said seed-delivering spout, a rear caster wheel supporting the rear end of the frame, and means for rocking said axle to raise and lower the furrow-opener. 110

5. In a planter, the combination of a body frame, a double mold board furrow-opener, a rear caster wheel supporting the said frame, supporting wheels for carrying the forward end of the frame, means for raising and lowering the said furrow opener in the frame, a hopper and seed-dropping mechanism supported on the forward end of the frame, and a seat supported on the frame in the rear of said hopper and seed-dropping mechanism.
6. A lister comprising a frame, a furrow opener, a bail-shaped axle, a bail, bearings for connecting the outer portions of said axle and bail with the frame, bearings for connecting the swinging or middle portions of the axle and bail with the furrow opener, a rear wheel for supporting the frame, a seed dropping mechanism and a seat mounted on the said lister, means for rocking the axle in its bearings on the frame to raise and lower the furrow opener, and means for driving the seed mechanism from one of said wheels.
7. A lister comprising a frame, a bail-shaped axle mounted in bearings on the forward portion of the frame, the bail or middle portion of said axle extending forward, wheels on said axle, a bail carried by the rear portion of said frame, said bail extending forward, a furrow opener mounted on the forward portions of said bail and bail-shaped axle, a rear caster wheel supporting the frame, seed-mechanism carried by the frame, means for driving said mechanism from one of said wheels, a seat on the frame in rear of said seed mechanism, and means for rocking said axle in its bearings on the frame to raise and lower the furrow opener in the frame.
8. The combination of a furrow opener, a frame, a bail-shaped axle mounted in bearings on the forward portion of the frame, the middle portion of said axle extending forward to support the furrow opener, wheels on said axle, seed mechanism on the frame, means for driving the seed mechanism from one of said wheels, and means for rocking the axle in its bearings on the frame to raise and lower the furrow opener in the frame.
9. The combination of a frame, seed mechanism on the frame, a furrow-opener hung in the frame below the seed mechanism, a seed spout carried by and in rear of the furrow opener, a seed-delivering connection between the said mechanism and spout, wheels supporting the frame, a connection from a front wheel to the seed mechanism for driving the latter, and means dependent on the position of the front axle for raising and lowering the furrow opener in the frame.
10. A lister comprising a seed mechanism, a furrow opener, a transversely disposed movable shaft for operating said mechanism, an upwardly movable member engaging said shaft, a frame supporting the shaft and furrow
- opener, and means for lifting the furrow 65 opener in the frame to raise said member and thereby shift the shaft endwise to disconnect the seed mechanism.
11. A lister comprising a frame, a furrow opener having a beam hung in said frame, an arch on the frame, a seed mechanism on said arch, wheels supporting said frame, means for driving said mechanism from one of said wheels, a rear caster wheel, and a seat on the rear end of the frame, said arch straddling 75 the beam of said furrow opener.
12. A lister comprising a seed mechanism, a movable shaft for operating said mechanism, a vertically disposed bar provided with a slot in which said shaft extends, a cam on 80 said bar, means on said shaft for engaging said cam, and means for raising said bar to shift the shaft endwise and thereby disconnect the seed mechanism.
13. A lister comprising a frame, an axle 85 journaled in bearings on said frame, a furrow opener hung on said axle, front wheels on said axle, a rear caster wheel, a seed mechanism operated from one of said wheels, and means for rocking said axle in the front 90 wheels to raise and lower the furrow opener.
14. A three wheeled lister comprising a frame and a furrow opener hung therein and a seed mechanism mounted thereon and driven from one of the forward wheels and 95 means operable from a seat carried by the frame in rear of the seed mechanism for raising and lowering the said furrow opener.
15. A lister of the frame type having two forward wheels and a rear caster wheel and 100 provided with an axle adapted to be rocked in the forward wheels for raising and lowering the furrow opener without raising and lowering the seed mechanism supported on the forward portion of the frame and driven from 105 one of the forward wheels.
16. A lister comprising a frame, a rear caster wheel for said frame, a seat on the rear portion of said frame, a bail mounted in bearings on the rear portion of said frame and extending forward therefrom, a bail-shaped axle mounted in bearings on the forward portion of said frame and extending forward therefrom, a furrow opener having a beam hung on said bail and axle, front wheels on 110 said axle, a seed mechanism mounted on the frame and driven from one of said forward wheels, means for rocking the axle in the forward wheels to raise and lower the furrow 115 opener, and means for locking the furrow 120 opener in different positions.

Signed by me at Fort Madison, Lee county, Iowa, this 30th day of August, 1906.

SAMUEL H. TINSMAN.
